DOUP HEDDLE LOOM

Filed Sept. 2, 1933

3 Sheets-Sheet 3

A technical line drawing of a wooden structure, likely a door or panel, featuring a vertical grain pattern. A horizontal slot or track is visible on the left side. A circular fastener, possibly a lock or hinge, is attached to the vertical panel. The drawing is labeled 'Fig. 6' in cursive script to the right.

A technical line drawing of a wooden frame structure. The frame is composed of a vertical post on the left and a horizontal beam on the right. A diagonal brace connects the post to the beam. A horizontal board, labeled 24, is attached to the beam. A series of vertical slats, labeled 26, are attached to the board 24. A central vertical post, labeled 27, supports the slats. A circular fastener, labeled 29, secures the post 27 to the board 24. A small rectangular component, labeled 23, is attached to the board 24 near the bottom. A label 10 is positioned at the bottom left. A label 22 is located at the top right, pointing to the horizontal beam.

DOUP HEDDLE LOOM

William H. Hall, Jr., Trenton, N. J., assignor to
 Thermoid Rubber Company, Trenton, N. J., a
 corporation of New Jersey

Application September 2, 1933, Serial No. 688,019

5 Claims. (Cl. 139—47)

This invention relates to the weaving of pile fabrics, such as carpet, on a loom normally adapted for the weaving of plain non-pile fabrics, such as canvas or asbestos fabric of the character normally used in the making of brake linings and clutch facings, wherein the sheet or web of fabric after weaving on the loom is cut and folded to provide a required number of layers or plies in the finished frictionized material.

10 The loom is of an ordinary type of well known construction including the usual plurality of heddle frames for manipulating the warp threads in forming open sheds for the passage of the shuttle in carrying a weft thread through the open warp shed in the production of a common one-over-one or a twill weave; and normally is not equipped with any mechanism for forming a pile face on the fabric.

20 The present invention relates to equipment adapted to be incorporated in a loom of the type noted, whereby a plain pile faced fabric may be produced thereon, all as will be fully disclosed hereinafter, reference being had to the accompanying drawings, of which:

25 Fig. 1 is a longitudinal sectional elevation of sufficient of a loom of the type noted to illustrate the operation of the elements of the present invention as applied thereto;

30 Fig. 2 is a fragmentary view similar to Fig. 1, drawn to an enlarged scale, and illustrating certain parts of the mechanism in positions differing from those illustrated in Fig. 1;

35 Fig. 3 is a transverse elevation, partly in section, of mechanism shown in Figs. 1 and 2, as taken on the line 3—3 Fig. 1;

Figs. 3a, 3b, and 3c are small sized details of the cam unit shown in Fig. 3;

40 Fig. 4 is a perspective view of a doup heddle and its operating heddles in predetermined relation to a stationary pile wire in accordance with the present invention;

Fig. 5 is a fragmentary perspective of the doup and operating heddle-supporting means;

45 Fig. 6 is a fragmentary perspective view of the support for the rear ends of the stationary pile wires; and

Fig. 7 is a fragmentary perspective view of the support for the front ends of the stationary pile wires.

50 As shown in the drawings, the loom comprises the usual transversely extending breast beam 1, a series of transversely extending heddle frames 2, 3, 4, 5 and 6, in the present instance, and a lay 7 provided with the usual reed or comb having a

series of dents 8 formed by and between a series of laterally spaced blades 9, 9.

In the present instance the warp in the loom comprises a series of stuffer warp threads s, a series of chain warps c, a second series of chain 5 warps c¹ and a series of pile warps p, all of which extend longitudinally of the loom through the heddle frames and dents of the reed.

Also extending longitudinally of the loom, through the heddle frames and lay reed, is a series of pile wires 10, 10, the front ends of which terminate adjacent the breast beam 1 and are each provided with a head 11, clearly shown in Figs. 1 and 7.

15 Each head 11 is provided with a forwardly extending lug or projection 12, which is seated in a horizontal groove 13 formed in the rear face of a bridge beam 14; and a shoulder 15 abutting the rear face of the bridge beam 14, to prevent forward longitudinal movement of the pile wires 10, 10.

15 Each head 11 is provided with a rearwardly extending lug or projection 16 overhanging the forward end of the associated pile wire 10. 20 The projection 16, in each instance, is provided with a depending lip 17, the underside of which, and the corresponding upper side of the adjacent portion of each pile wire 10 are grooved as indicated at 18 and 19 respectively, to receive a thin 25 removable blade 20. Each blade 20 is provided with a cutting edge 21, which is disposed at an acute angle to the upper edge of the pile wire. The blade 20 is shouldered, as indicated at 22, to abut the rear edge of the projection 16, to prevent forward longitudinal movement of the blade 30 35 relative to the pile wire.

The rear end of each of the pile wires 10 is provided with a slot or eye 23, which is adapted to receive a readily removable bar 24 on which the 40 series of pile wires is threaded. The bar is supported by a rear beam 25 which extends transversely of the loom and is permanently fixed, at its opposite ends, to the side frames 26 of the loom, as indicated in Fig. 6. A staple or hook 27 is 45 provided adjacent each end of the bar 24 and rigidly secured in the rear beam 25, to receive the bar 24 and secure the same in fixed relation to the rear beam 25, each end of the bar 24 being provided with an opening 28 adapted to receive a 50 cotter pin 29, outside the staple 27, whereby longitudinal movement of the bar 24 is prevented.

The pile wires 10, while being stationary, insofar as longitudinal movement in the loom is concerned, are permitted a slight relative lateral 55

movement in the slot 13 at their forward ends and on the bar 24 at their rear ends, to prevent binding of the pile wires against the blades 9 of the reed, as the lay 7 reciprocates intermediate 5 the breast beam 1 and the first of the heddle frames 2.

The front ends of the pile wires 10 may be readily removed from the supporting slot 13 of the bridge 14 by the removal of a bar 30, the lower 10 surface of which forms the upper surface of the slot 13, which is secured to the bridge beam 14 by means of bolts 31, as clearly shown in Fig. 7.

The bridge beam 14 is spaced above the upper 15 face of the breast beam 1, to provide a fabric passage or slot 32, by means of blocks 33 disposed at the opposite ends of the bridge beam 14, between the said bridge beam and the said breast beam, the bridge beam 14, the blocks 33, and the breast beam 1 being secured together as 20 20 a unit by means of screws or bolts 34.

As shown in Fig. 1, the stuffer warps *s* are under the control of the heddle frame 6 while the chain warps *c* and *c'* are controlled by the heddle frames 4 and 5 respectively. The pile warps *p* 25 are each under control of a doup heddle 35.

Each doup heddle is under control of a front 30 operating heddle 36, carried by the heddle frame 2, and a rear operating heddle 37, carried by the heddle frame 3. Each doup heddle 35 is of a U-shaped form comprising a front leg 35a and a rear leg 35b which are joined by a semi-annular portion 35c and a cross element 35d forming a thread eye 35e at the lower end of each of the doup heddles 35 for the reception of one of the pile warps *p*.

As shown in Fig. 4, the upper end of each of the legs 35a and 35b of each doup heddle 35 is slotted, as at 35f, for the reception of a pair of supporting bars 38, 38. The bars 38, 38 are integrally joined at their opposite ends, as indicated at 39 in Fig. 5, to provide a common carrier for the doup heddles.

As indicated in Fig. 4, the operating heddle 36 is composed of two substantially similar heddle 45 elements 36a and 36b, each of which is provided at its lower end with a slot or eye 36c, for the reception of a bar 40. The upper end of each of the heddle elements 36a and 36b is provided with the slot or eye 36d, for the reception of a supporting bar 41. Intermediate its opposite ends the heddle element 36a is provided with an eye 36e and the heddle element 36b is provided with a laterally offset portion 36f which passes through the eye 36e of the heddle element 36a.

Similarly, the heddle element 37 is composed of substantially similar elements 37a and 37b which are provided at their lower ends respectively with eyes 37c for the reception of the supporting bar 42, and at their upper ends with eyes 37d for the reception of the supporting bar 43. Intermediate its opposite ends the heddle element 37a is provided with an eye 37e through which a laterally offset portion 37f of the heddle element 37b extends.

As clearly illustrated in Fig. 4, the doup heddle 35 is disposed intermediate the elements 36a and 36b of the operating heddle 36 and intermediate the elements 37a and 37b of the operating heddle 37, with the cross-bar 35d of the doup heddle 35 disposed below the laterally offset portions 36f and 37f of the operating heddles 36 and 37 respectively, and, as clearly shown in said figure, the pile warps *p* is disposed, for example, at the 75 right side of the operating heddle 36 from which

it passes laterally through the eye 35e of the doup heddle 35, between the operating heddles 36 and 37, to the left side of the said operating heddle 37.

The supporting bars 40 and 41 for the front operating heddles 36 are mounted in the front 5 heddle frame 2, while the supporting bars 42 and 43 of the rear operating heddles 37 are mounted in the rear heddle frame 3.

The heddle frames 2 and 3 respectively comprise upper transverse rails 44 and 45 and lower 10 transverse rails 46 and 47 rigidly connected by end bars 48 and 49. The end bars 48 and 49 are provided with slots 50 and 51 respectively through which the operating heddle-supporting bars 40, 15 41, 42 and 43 project.

The upper rails 44 and 45 of the heddle frames 2 and 3 respectively are provided with straps 54, 54 and 55, 55 respectively to which are secured lower ends of chains 56 and 57 respectively, said chains passing vertically upward, over and around 20 axially aligned sheaves 58, 58, with their opposite ends 59, 59 respectively connected to horizontally disposed longitudinally movable operating bars 60, 60, only the front one of which is 25 shown in Fig. 3.

The operating bars 60, 60 are slidably mounted on a cross member 26a of the frame of the loom. Each of the bars 60 is connected at one of its ends to a rocker arm 62 by a link 61. The rocker arm 62 associated with the front heddle frame 2 is connected by a link 63 to an upper arm 64a of a rockable lever 64, which latter is pivotally mounted at 65 to a fixed portion of the loom. The rocker arm 62, associated with the rear heddle frame 3, 35 is connected by a similar link 63 to the upper arm 66a of a rockable lever 66, which is also pivoted at 65 to the frame of the loom.

Each of the lower rails 46 and 47 of the front and rear heddle frames 2 and 3 respectively is 40 provided with straps 67, 67, to which are operatively connected one end of each of a pair of chains 68, 68, the opposite ends 69, 69 of which are operatively connected to lower horizontally 45 slidable operating bars 70 which are mounted on a transverse member 26b of the frame of the loom, said chains passing around sheaves 71, 71, as clearly illustrated in Fig. 3.

The lower operating bars 70, for the heddle frames 2 and 3 respectively, are connected by 50 links 73, 73 to lower arms 64b and 66b of levers 64 and 66 respectively.

Rockably mounted on the pivot 65, intermediate the levers 64 and 66, is a third lever 75, an upper arm 75a of which is connected by a link 55 76 to one arm 77a of a bell-crank 77, said bell-crank being pivotally mounted at 78 to the transverse member 26a of the frame of the loom. The arm 77a of the bell-crank 77 is connected by a link 76a to one arm 79a of a bell-crank 79, which latter is pivotally mounted at 80 to the said transverse frame member 26a. The second arms 77b and 79b, of the bell cranks 77 and 79, respectively, are connected by links 81, 81 to the opposite ends respectively of a horizontal bar 82, disposed above 65 the heddle frames 2 and 3 as clearly illustrated in Figs. 1, 3 and 5.

Passing over the top of the supporting bar 82 and extending downwardly at each of the opposite sides thereof, and to the front of the heddle frame 2 and to the rear of the heddle frame 3, are strap members 85 of an inverted U-shaped form, the lower ends of the front and rear legs 85a and 85b of which are hooked, as indicated at 84 in Fig. 5, said hooks engaging the bars 38, 75

38 which comprise the common carrier for the doup heddles 35.

As shown in Figs. 3, 3a, 3b and 3c, the levers 64, 66, and 75 are adapted to be rocked in predetermined timed relation with respect to each other by cams 90, 91 and 92 respectively, all of which are secured to a common cam shaft 93 which is rotatably mounted on and at one side of the loom and which is driven in predetermined timed relation to the lay and shuttle-operating mechanism of the loom, in the usual manner.

The levers 64, 66 and 75 are provided with projecting arms 64c, 66c and 75c respectively, which at their outer ends carry cam followers 64d, 66d and 75d respectively.

The cam 90 is provided with dwell portions 90b, 90b of the cam surface or groove which are concentric to the axis of the shaft 93 and alternate with radially depressed cam surface or grooved portions 90a, 90a. The groove of the cam 91 is provided with similar dwell portions 91b, 91b which alternate with the active radially depressed portions 91a, 91a.

25 The cams 90 and 91 are secured to the shaft 93 in ninety degree relation to each other, that is, the dwell portions 91b, 91b of the cam 91 are aligned with the active cam portions 90a, 90a of the cam 90, and the dwell portions 90b, 90b of the cam 90 are aligned with the active portions 91a, 91a of the cam 91. While each of the cams 90 and 91 is provided with two dwell or high portions, radially speaking with respect to the axis of the shaft 93, the cam 92 is provided with 30 four radially high portions 92b, which alternate with four radially depressed portions 92a, 92a, the radially high portions 92b of the cam 92 being aligned with the opposite ends of the dwell portions 90b and 91b of the cams 90 and 91 respectively where the said ends of the dwell portions of the cams 90 and 91 overlap one with the other, circumferentially speaking.

With the cams 90, 91 and 92 in such relation to each other on the cam shaft 93 and the cam followers 64d, 66d and 75d, respectively, in the positions shown in Figs. 3 to 3c inclusive, the heddle frames 2 and 3 and the doup heddle carrier 38 are all in raised positions illustrated in Figs. 1 and 3.

50 Upon rotation of the cam shaft 93, in the direction of the arrow in Fig. 3, the cam follower 64d will ride out of the dwell portion 90b of the cam 90 into the first active or depressed portion 90a, thereby rocking the lever 64 and effecting a lowering of the front heddle frame 2, the rear heddle frame 3 remaining in its elevated position by reason of the cam follower 66d remaining in the dwell portion 91b of the cam 91. At the same time the cam follower 75d rides from the high portion 92b of the cam 92 into the active portion 92a of the said cam 92, permitting the doup heddle carrier 38 to drop in synchronism with the front operating heddle frame 2.

55 Dropping of the heddle frame 2 effects lowering of the front operating heddles 36, whereby the offset portions 36f of said operating heddles engage the cross bar 35d of the doup heddles 35, whereby the doup heddles and the pile warps p controlled thereby are carried down below and 60 to the right side of the stationary pile wires 10 with which the doup heddles are respectively associated.

While the doup heddles 35 are down, the heddle frames 4, 5 and 6 are operated in the usual manner to control the chain warps c and c¹ and

75 the stuffer warps s in coordination with the weft-inserting means (not shown) to insert a weft thread in the open warp shed formed by the said warp threads, whereby the pile warps p will be tied into the fabric at one side of each of the stationary pile wires 10.

As the shaft 93 continues to rotate in the direction of the arrow, the cam follower 64d will move to the second dwell portion 90b of the cam 90, whereby the front heddle frame 2 is 10 raised to its normal elevated position.

Prior to this invention all commercially operating doup heddles have been returned to their normal elevated positions by means of springs, and due to friction of the warp threads against 15 the doup heddles, which is a factor that varies with conditions in the particular loom with which the doup heddles are associated, the doup heddles frequently stuck in the lower positions, causing smashes and damage to the fabric and the 20 loom elements, due to the fact that when the operating frames rise the tension of the springs controlling the doup heddles is not sufficient to raise the doup heddles accordingly.

In the present instance and according to the 25 present invention, when the front heddle frame 2 rises the common carrier 38 for the doup heddles 35 will also be positively raised by the cam follower 75d riding into the second of the high portions 92b of the cam path in the cam 92, which 30 rocks the bell-crank 77 and 79 and through the positive linkage connecting said bell-crank with the carrier 38 positively raises the doup heddles 35 to their normal elevated positions.

The cam follower 66d then rides out of the 35 dwell portion 91b of the cam 91 and into the active portion 91a of said cam, whereby the rear heddle frame 3 is lowered, consequently lowering the rear operating heddles 37, by which the cross or offset portions 37f of said operating 40 heddles engage the cross bars 35d of the doup heddles 35 and carry said doup heddles and the pile threads p controlled thereby down to the left side of each of the correlated pile wires 10, whereby the pile threads p are formed into 45 loops p¹ transversely of and around the upper edges of the pile wires 10. The heddle frames 4, 5 and 6 and the weft-inserting mechanism is then operated again to tie the pile threads p into the fabric at the left side of the pile wires 50 10, whereupon the cam follower 66d again rides on to one of the high portions 91b of the cam 91, thereby raising the rear operating heddle frame 3 to its normal elevated position. At the same time the cam follower 75d rides on to 55 another of the high portions 92b of the cam 92, thereby positively raising the carrier 38 and all of the doup heddles 35 connected thereto.

During the falling and rising movements of the frame 2, the frame 3 is held in its normal 60 elevated position by reason of the cam follower 66d riding one of the high portions 91b of the cam 91; and during the rising and falling movements of the frame 3 the frame 2 is held in its normal elevated position, by reason of the cam 65 follower 64d being under control of one of the high or dwell portions 90b of the cam 90, while the doup heddle carrier 38 rises and falls with each of the said corresponding movements of the frames 2 and 3.

70 As the cam shaft 93 continues to rotate the operations just described are successively repeated, the frames 2 and 3 being alternately lowered to carry the doup heddles 35 and the pile threads p first to the right and then to the 75

left of the pile wires 10. After each lowering of the doup heddles the same are positively raised by the positively acting mechanism including the cam 92, the doup heddle carrier 38, and the intermediate linkage.

Each time a course of pile loops p^1 is formed over the pile wires 10 the lay 7 beats-up the weft thread by which the pile loops are tied into the fabric, which advances the fabric and the pile loops longitudinally of the pile wires 10 bringing the pile loops into engagement with the cutting edge 21 of the pile cutting blades 20, whereby the loops p^1 are cut; and by the beat-up movements of the lay 7 the finished fabric is passed through the slot 32 formed between the bridge beam 14 and the breast beam 1.

It will be understood that the heddle frames 4, 5 and 6 are operated by cams similar to those described, the cams for the frames 4, 5 and 6 having predetermined cam paths for operating the said heddle frames in the proper order and manner coordinately with the cams 90, 91 and 92, for producing the weave of the foundation of the fabric F with which the pile loops p^1 are incorporated.

I claim:

1. In a loom comprising a series of heddle frames, the combination therewith of a series of stationary pile wires extending through the heddle frames, a series of doup heddles respectively associated with and normally disposed above the pile wires, a pair of actuating heddles operatively connected to each doup heddle and to a pair of said heddle frames respectively, a pair of cams having alternating and relatively staggered dwell and active cam surfaces alternately raising and lowering said pair of heddle frames to lower the doup heddles first on one and then on the opposite side of the respectively associated pile wires, and a cam having active cam surfaces coinciding respectively with each of the active frame raising cam surfaces of the first said cams for raising the doup heddles after each lowering thereof, and idling surfaces coincident with the active frame-lowering cam surfaces of the first said cams to permit said heddle frames to lower said doup heddles without interruption by the doup heddle raising means.

2. In a loom comprising a series of heddle frames, the combination therewith of a series of pile formers extending through the heddle frames, a series of doup heddles respectively associated with and normally disposed above the pile formers, a pair of actuating heddles operatively connected to each doup heddle and to a pair of said heddle frames respectively, means alternately operating said pair of heddle frames to lower the doup heddle first on one and then on the opposite side of the respectively associated pile formers, positive acting means for raising the doup heddles after each lowering thereof, comprising a cam, a lever having a cam follower co-functioning with said cam, a common carrier for and by which all of said doup heddles are normally supported, a bell-crank pivotally mounted above said common carrier, means operatively connecting one arm of said bell-crank to the common carrier, and means operatively connecting the second arm of the bell-crank to said lever.

3. In a loom comprising a series of heddle frames, the combination therewith of a series of pile formers extending through the heddle

frames, a series of doup heddles respectively associated with and normally disposed above the pile formers, a pair of actuating heddles operatively connected to each doup heddle and to a pair of said heddle frames respectively, means alternately operating said pair of heddle frames to lower the doup heddle first on one and then on the opposite side of the respectively associated pile formers, positive acting means for raising the doup heddles after each lowering thereof, comprising a cam, a lever having a cam follower co-functioning with said cam, a common carrier for and by which all of said doup heddles are normally supported, a pair of bell-cranks pivotally mounted in spaced relation to each other above and substantially in the plane of the common carrier for the doup heddles, means operatively connecting one arm of each of said bell-cranks to the common carrier, a link operatively connecting the second arms of the bell-cranks, and a link connecting said lever with one of the arms of one of said bell-cranks.

4. In a loom comprising a series of heddle frames, the combination therewith of a series of pile formers extending through the heddle frames, a series of doup heddles respectively associated with and normally disposed above the pile formers, a pair of actuating heddles operatively connected to each doup heddle and to a pair of said heddle frames respectively, means alternately operating said pair of heddle frames to lower the doup heddle first on one and then on the opposite side of the respectively associated pile formers, positive acting means for raising the doup heddles after each lowering thereof, comprising a cam, a lever having a cam follower co-functioning with said cam, a common carrier for said doup heddles operable within the actuating heddle frames adjacent said actuating heddles, a bar disposed above and horizontally parallel to said heddle frames, straps connecting said bar to said common carrier in spaced relation longitudinally of the bar, and means operatively connecting said bar to said lever.

5. In a loom comprising a series of heddle frames, the combination therewith of a series of pile formers extending through the heddle frames, a series of doup heddles respectively associated with and normally disposed above the pile formers, a pair of actuating heddles operatively connected to each doup heddle and to a pair of said heddle frames respectively, means alternately operating said pair of heddle frames to lower the doup heddle first on one and then on the opposite side of the respectively associated pile formers, positive acting means for raising the doup heddles after each lowering thereof, comprising a cam, a lever having a cam follower co-functioning with said cam, a common carrier for said doup heddles operable within the actuating heddle frames adjacent said actuating heddles, a bar disposed above and horizontally parallel to said heddle frames, straps connecting said bar to said common carrier in spaced relation longitudinally of the bar, a pair of relatively spaced and pivotally mounted bell-cranks above said horizontal bar, a pair of links operatively connecting the opposite ends of the bar to one arm of each of the bell-cranks, a link operatively connecting the second arms of said bell-cranks, and a link operatively connecting the said second arm of one of said bell-cranks with said lever.

WILLIAM H. HALL, JR.
